UNITED STATES PATENT OFFICE.

JOHN ROEBUCK, OF BROOKLYN, NEW YORK.

FLUE STOPPER OR COVER.

SPECIFICATION forming part of Letters Patent No. 414,328, dated November 5, 1889.

Application filed February 26, 1889. Serial No. 301,186. (No model.)

To all whom it may concern:

Be it known that I, JOHN ROEBUCK, a resident of the city of Brooklyn, Kings county, New York, have invented an Improved Flue Stopper or Cover, of which the following is a specification.

This invention relates to stoppers or covers that are placed over flue-openings in chimneys and fire-boards; and it has for its object to improve the means for holding the stopper or cover over the opening.

The invention consists in the details of improvement and the combinations of parts that will be more fully hereinafter set forth.

Reference is to be had to the accompanying drawings, forming part of this specification, in which—

Figure 1 is a face view of my flue cover or stopper; and Fig. 2 is a back view of the same, showing the means for holding it over the flue-opening. Fig. 3 is a cross-sectional view of the flue stopper or cover, showing the manner of holding the stopper over the flue-opening in the chimney. Fig. 4 is a similar view showing the stopper as covering the opening in the board of a fire-place; and Fig. 5 is a detail view, enlarged, of part of the flue-stopper.

In the accompanying drawings, the letter A represents a flue stopper or cover which consists of a plate of metal or the like of suitable size and outline, which plate may be decorated in any manner desired on its face, while on the back the means for retaining the cover in the flue are carried.

a is a small plate that is or may be carried by the stopper A on its outer side, which plate a may have any suitable ornamentation.

B are two springs that are carried by the stopper A, which springs may be flat or round in cross-section. The springs B in their normal condition extend along the inner face or side of the flue-stopper A, and they are connected to said stopper by a sleeve D, that is carried by said stopper, the ends of the springs B being passed into said sleeve and overlapped, as shown in Fig. 3.

The sleeve D consists of a metal strip bent to the proper size in cross-section to receive the springs B, the ends b of said strip forming lugs, that are passed through an opening in the cover A and then bent over and laid in line with the face of the flue-stopper A, as

shown in Fig. 5. By this means the sleeve D is kept from turning and is also held upon the flue-stopper; but the springs B may be carried by the flue-stopper in any other suitable manner.

The springs B are of the following construction: After leaving the sleeve each spring is bent outward toward the plate A, as at e, so as to touch the plate A, or nearly so, and its end is then curled inward, as at f. The springs B, by being curved as shown at e, are adapted to be turned backwardly from the position shown in Fig. 4 into that shown in Fig. 3, the curved part e acting somewhat like a spring-hinge to permit the free ends f of the springs to be swung. By this means when the stopper is to be placed over a flue-opening E the ends of the springs B will be bent inwardly on the point e and passed into the flue until the stopper A rests against the wall, as shown in Fig. 3, when the outward spring tendency of the springs will press the curved part f of the springs against the inner walls of the flue, which, being at right angles to the stopper A, receive the ends of the springs, and thereby retain the cover in position. If the flue-opening E be larger or smaller, the springs B will adapt themselves to the opening, so as to hold the stopper securely in position. The springs may in some cases be moved outwardly or inwardly slightly in their holding-sleeve D to compensate for the difference in diameter of the flue-opening when desired.

When the flue-stopper A is to cover the opening in a board F that is placed in front of a fire-place, the springs will be passed through the opening, but will not be bent at the point e. They will in this case extend along the back of the fire-board F, the fire-board thereby coming between the stopper and the springs. The curvature of the springs, as shown, gives a tension, which, by pressing against the fire-board, holds the flue-stopper in position.

It is evident that instead of having two separate springs B, one double spring of the same character, that extends on both sides of the holding-sleeve D, may be used with the same results.

Having now described my invention, what I claim is—

1. The flue-stopper A, combined with the

springs B, that extend along the back of the same, said springs being curved outward at e into contact with the stopper A, and curved backward at the ends at f and adapted to press 5 against the flue-walls at right angles to the stopper and against a fire-board parallel with the stopper, substantially as described.

2. The flue-stopper A, and the sleeve D, carried by said stopper, combined with the springs 10 B, that extend along said stopper and project from opposite sides of the sleeve D, said springs

being curved outward at e into contact with the stopper A, and curved backward at the ends at f, and thus enabled to be bent inwardly to press against a wall at right angles to the stopper, and also adapted to press against a wall 15 that extends in line with the stopper, substantially as described.

JOHN ROEBUCK.
